UNITED STATES PATENT OFFICE.

GEORGE F. MINNIS, OF CHICAGO, ILLINOIS.

SAFETY-ANCHOR.

1,319,890.

Specification of Letters Patent.

Patented Oct. 28, 1919.

Application filed August 15, 1917. Serial No. 186,280.

To all whom it may concern:

Be it known that I, GEORGE F. MINNIS, a citizen of the United States, residing at Chicago, in the county of Cook and State 5 of Illinois, have invented certain new and useful Improvements in Safety-Anchors, of which the following is a specification.

This invention relates to improvements in safety devices for window washers and 10 more particularly to a support for engagement by the window washer's clips.

One of the objects of my invention is to provide a support for attachment to a metal window sash having a transversely 15 concaved vertically extending surface on its outer edge adjacent the portion to be embedded in a concrete post.

Another object of my invention is to provide such a support in which the headed 20 projections over which the clips slide are provided with shoulders intermediate the head and base for spacing the clip outwardly to prevent its engagement with either the window or other adjacent parts.

25 Still further objects of the invention are to provide a sturdy, rigid attachment member which will be efficient in operation and not liable to breakage.

Still other and further objects will be 30 come apparent to those skilled in the art from a consideration of the following description and drawing, wherein:

Figure 1 is a front elevation of a window sash showing my improved support 35 in position.

Fig. 2 is a horizontal sectional view on the line 2-2 of Fig. 1, showing a window washer's clip attached to the support, and

Fig. 3 is a vertical sectional view on the 40 line 3-3 of Fig. 2.

Considerable difficulty has been found in providing a support for engagement by a window washer's harness at the point of juncture between a metal window sash and 45 concrete wall or post, where the edge of the sash is embedded in the concrete. This is particularly true of the metal window frames known as fenestra, wherein a very small amount of metal is exposed between 50 the concrete wall and glass window.

The vertical strip of metal forming a portion of the outer side of the window sash has a transversely concaved surface 55 adjacent the glass and I have so arranged my improved support as to permit its attachment to this surface and yet space the

clip outwardly away from the included angle between the glass and concrete. This I accomplish by providing the base from which the clip engaging lug extends, with 60 a transversely convex surface to interfit the concaved surface on the frame and the outwardly extending headed projections over which the clips slide are provided intermediate the head and base with a shoulder 65 which holds, or spaces, the clip outwardly away from the window and concrete, holding it in the desired position.

In the specific embodiment of the invention which I have chosen to illustrate for 70 the purpose of making a full and complete disclosure, the numeral 10 indicates a metal window sash formed of an angle iron having an inwardly extending leg 11 and outwardly extending leg 12. A flange 13 projects from the leg 11, near its juncture with the leg 12 to provide an outward abutment for the window glass 14 which is secured in position by suitable cement or other material 15. Between the outer face 80 of the flange 13 and the inner edge of the leg 12 a concaved vertically extending surface 16 is provided and it is against this vertically extending concaved surface that I attach my support. 85

The support comprises a vertically extending base 17 having its rear surface convexed, as at 18, to interfit with the concaved surface 16 of the window sash. From the outer convex surface 19 two spaced apart 90 headed projections 20 extend for engagement with the window washers slotted clip, indicated in general by the numeral 21. These projections 20 have heads 22 formed on their outer ends and flanges or shoulders 23 intermediate the head and base, forming annular grooves at 24 between the heads 22 and flanges 23, in which the slotted clip 21 slides. The head 23 therefore serves to space the clip outwardly away from the 100 supports to prevent any possible side movement of the clip such as might cause its engagement with the window 14. This arrangement of the shoulder adjacent the head on the end of the projection also serves 105 to guide the clip as it is slid over the projection and holds it firmly in the position shown in Fig. 2, preventing wobbling or side movement.

The base may be secured to the sash in 110 any suitable manner, as for example, by the screws 25 taking through countersunk

holes in the base into threaded holes in the sash. The ends of the screws 25 may be headed over, as at 26, for additional security.

5 Whereas I have illustrated and described but a single embodiment of my invention, it will be evident to those skilled in the art that various changes or modifications may be made without departing from the spirit 10 of the invention or the scope of the appended claims.

Having described my invention, what I claim is:—

1. A device for engagement with a window washer's slotted safety clip and for attachment to a window frame between angularly disposed walls, comprising an elongated base 17, two spaced-apart headed projections, 20, each projection provided with spaced apart heads, 22 and 23, to provide a space 24 to receive the clip 21, the inner head, 23, being spaced apart from the base 17 a distance sufficient to permit the clip to clear the wall and glass when the base

is located at the junction of angularly related walls. 25

2. In combination with a metal window sash having an abutment to receive the window glass and a vertically extending concaved surface on the outside of said abutment, a supporting means having an elongated base part with its rear or under surface convex to fit said concave surface, said supporting means having a plurality of spaced apart headed projections, each projection being provided with an outer head and an intermediate head spaced apart to receive a window washer's slotted clip, said intermediate head being spaced from said support, said heads extending at an angle 40 with reference to the sides of the angle between said window glass and frame, whereby the clip is held away from the glass and frame to prevent engagement therewith. 35

In testimony whereof I hereunto set my 45 hand.

GEORGE F. MINNIS.
